WILLIAM C. HICKS, OF NEW YORK, N. Y.

Letters Patent No. 72,636, dated December 24, 1867.

IMPROVED APPARATUS FOR GRINDING AND POLISHING CYLINDRICAL CONCAVE SURFACES.

The Schedule referred to in these Letters Patent and making part of the same.

TO ALL WHOM IT MAY CONCERN:

Be it known that I, WILLIAM C. HICKS, of New York, of New York county, in the State of New York, have invented certain new and useful Improvements in Finishing up Concave Surfaces; and I do hereby declare that the following is a full and exact description thereof, reference being had to the accompanying drawings, making part of this application.

Previous to my invention it has been customary to turn out and finish the interior or internal cylindrical surface of steam-engine pump and other cylinders with a suitable tool arranged upon an ordinary boring-bar; (the cylinder being operated upon, being generally secured to the carriage of a lathe, and the boring-bar mounted and turned on the lathes' centres.) It has been found exceedingly difficult, if not impossible, in practice, to turn out and finish, with any very great degree of perfection, the interiors of cylinders by this well-known and I believe universally-practised mode of operation.

My invention has for its object to overcome all the practical difficulties heretofore encountered in the operations of boring and finishing the interior of cylinders, and afford a means by which any concave or cylindrical surface may be finished very readily to a state of great perfection, both as to accuracy of curvature and smoothness of surface; and to these ends my invention consists in the employment of one or more rotating grinding-wheels, or disks, or cutters, in combination with a suitable sustaining-bar and driving-mechanism, the whole so arranged and operating that the said rotatory grinding-disk or disks may be made to rotate in contact with the surface to be finished, while said surface is made to reciprocate, as will be presently more fully described.

To enable those skilled in the art to make and use my invention, I will proceed to describe it more fully, referring by letters to the accompanying drawings, in which—

Figure 1 is an elevation of an apparatus adapted to carry out my invention.

Figure 2 is a vertical longitudinal section of the same.

Figure 3 is a vertical cross-section at the line xx , fig. 1, and

Figure 4 is a vertical cross-section at the line yy , fig. 1.

In the several figures the same part is designated by the same letters of reference.

A is a shaft or bar, which should be mounted to turn freely on centres bb , and which may be provided with a pulley, C, by which, through the medium of a driving-belt, the necessary rotatory motion may be imparted to the said shaft A; or, where said shaft is placed in the centres of an ordinary engine-lathe, it may be driven from the face-plate of such lathe in the manner usually adopted for turning work in a lathe. At the end of said shaft A (opposite to that at which it is coupled to the lathe or receives its driving-pulley C) is secured upon it a flanged disk or collar, D, upon which is arranged a driving-pulley, E, in the manner clearly shown in the drawings, which is formed and arranged so as to drive from its internal surface (either by friction or gear-teeth) a wheel, f, which is keyed on to the end of a small shaft, G, mounted to turn freely in boxes formed in the stands hh . This shaft G carries the grinding and polishing-wheels or disks ii , which are intended to operate upon the cylinder-surface to be finished up. The stands hh , if deemed expedient, may be so arranged with the shaft or bar A as to be adjustable, in order that the shaft G, with its grinding-wheels ii , may be set nearer to or further from the centre of motion of bar A, for the purpose of effecting a greater or less degree of cutting or grinding of the stock being operated upon. The pulley E is driven by a suitable belt, k, and should be made to rotate much more rapidly, in the same direction, than the main shaft A.

In figs. 2 and 4 I have shown, in blue lines at m , the cylinder which is supposed to be undergoing the operation of being ground and finished at its internal surface, and at o the carriage to which it is secured, and by which it is carried along in the direction of its own axis and that of the main shaft A.

The operation of such an apparatus, as just described, will be readily understood to be as follows, viz: The cylinder to be finished (having been previously bored out very nearly true by means of an ordinary boring-bar and turning-tool) is adjusted and secured upon the reciprocating carriage o in such a manner as to be as nearly as possible concentric with the circle in which the grinding-wheel travels. The main shaft A and the counter-shaft G, being then each set in motion, and the carriage o made to move along, the cylinder m is carried along, while the rapidly-rotating grinding-wheels hh are carried around within it and against its internal surface, (as clearly illustrated at fig. 2,) whereby the interior of said cylinder is perfectly ground and finished in a very

short time. This operation may be repeated to give a still higher finish to the cylinder-surface, if desired, by either substituting, for the grinding-wheels, others of a little greater diameter, (and, if expedient, of a different material or character,) or by adjusting the shaft G so as to cause the wheels or disks to take a fresh bite, and then passing the cylinder along again in contact with the rotating grinders.

It will be seen and understood that, by means of a grinding-disk, (or series of them,) or rotating cutter, travelling around in a circular orbit, while rapidly revolving on its own axis, the concave surface with which such grinder or cutter comes in contact will be ground or cut away in a perfect circle, and that by imparting at the same time a perfectly straight reciprocating motion to the work, the interior of the cylinder will be ground or cut to a perfectly cylindrical shape, and at the same time may be given an exceedingly smooth or polished surface, which are desiderata, long desired, and of the highest importance in many kinds of work.

It will be readily understood, by the skillful mechanic, that the details of construction of an apparatus to carry out my invention, may be varied according to circumstances and the character of the work to be done. In finishing up small cylinders, I propose to insert the main bar (such as seen at A) in an ordinary engine-lathe, and mount the cylinder upon the carriage of the lathe, and I have practised my invention in this way very successfully.

In finishing the interior of very large cylinders it may be found necessary to rig up the apparatus so that, while the cylinder remains stationary, the grinding-wheels shall not only travel around within the cylinder and rotate on their axes, but also travel along longitudinally in the cylinder, and various arrangements of the details of the apparatus may be adopted to carry out this idea, the gist of my invention consisting in having the grinders, or rotatory grinding-wheels, roll, or disk, (or whatever may be employed as a grinder,) have, at the same time with their rotatory motion, a motion in the direction of the circle of the curved surface being operated on, while the cylinder moves along, (or the grinders move along within the cylinder, if deemed expedient.)

It may even be found expedient in some cases to rotate the cylinder in lieu of having the grinders travel around within it, but all such changes or transpositions of motions, it will be seen, do not vary the effect produced materially, and are only different ways of carrying out my invention, and effecting the same relative motions of the grinding-surfaces with the surface being ground and finished.

Having fully explained my invention, so that those skilled in the art can make and use it, what I claim as new, and desire to secure by Letters Patent, is—

The method of finishing up concave surfaces, substantially as hereinbefore described, that is to say, by means of rotatory tools running in contact with the surface being operated upon, while the said tools and surface are moved (by any suitable mechanism) relatively to each other, in the manner set forth.

In testimony whereof, I have hereunto set my hand and seal, this thirtieth day of August, 1867.

WM. CLEVELAND HICKS. [L. s.]
